ATTORNEYS.

UNITED STATES PATENT OFFICE.

HENRY W. SWITZER, OF HAMILTON, ONTARIO, CANADA, ASSIGNOR TO WILLIAM H. HEIMBACH, OF SNYDER, NEW YORK.

WRENCH.

Application filed March 4, 1926. Serial No. 92,142.

This invention relates to improvements in wrenches, and more particularly to a quick acting jaw holding and releasing means or mechanism for wrenches of that type which 5 have a jaw slidably arranged so as to move towards and from a fixed jaw by means of a rotatable operating worm or screw engageable with rack teeth on either the sliding jaw or the wrench body. 10 One object of the invention is to provide wrenches of the kind described with quick releasable holding means adapted to prevent the operating screw from turning and the sliding jaw from moving when pressure is applied to said jaw in a direction away from 15 the fixed jaw, but which, nevertheless, permits the sliding jaw to be quickly moved towards the fixed jaw by pressure exerted on the sliding jaw in the direction of the fixed 20 jaw without the necessity of separately actuating said operating screw.

Another object is to provide quick releasing means adapted to be readily actuated to release said jaw holding means to permit 25 said sliding jaw to be easily moved away from the fixed jaw without the necessity of separately actuating the operating screw.

Other objects are to improve jaw operating or holding and releasing means for 30 wrenches in the other respects hereinafter specified and claimed.

In the drawing:

The figure is a fragmentary side elevation partly in section, of a wrench having a 35 slidable jaw, and which is provided with the quick acting holding and releasing means for said jaw embodying the invention.

The quick acting jaw holding and releasing means is shown in connection with a well 40 known form of wrench, the latter having a head 35 provided with a fixed jaw 36 formed at one end of a handle 36^a, and a jaw 37 arranged to slide on said head towards and from said jaw 36. For this purpose, the 45 head is slotted at 38, and the jaw 37 is provided with a sleeve portion 39 which embraces the outer portion of the head and has a web or guide part extending within said slot. The slot 38 is preferably formed in the head 35 with an open end which may 50 be closed by means of the detachable plate 41 for permitting assembly and subsequent detachment of the sliding jaw from said head.

55 The jaw 37, is provided with an operating

screw 15^a, the threads of which engage in teeth 17^a on the adjacent end of the head. The screw is provided with a cone 20^a adapted to frictionally engage a tapered seat 21^a in the sliding jaw by the pressure exerted on said screw by the spring 23^a.

The cone 20^a projects part way into the transverse hole 29^a in which the plunger 28^a is arranged, and the ball or member 30^a, in its inoperative position, engages the tapered 60 face of the cone 20^a. A cam 34^a is adapted, when the plunger is moved inwardly, to force the ball against the cone and move the screw 15^a outwardly and its cone off its seat 21^a. The ball rides up on the end of the cone at 65 the inward limit of movement of the plunger to hold the operating screw in released position. In order to positively return the plunger 28^a to its inoperative position and permit the spring 23^a to reengage the cone 70 of the operating screw with its seat, a spring or other yielding member 40, fixed to the sliding jaw and having its free end engaging the inner end of the plunger, may be provided. By this construction, the jaw 37 is 75 prevented from endwise movement away from the fixed jaw 36, as pressure exerted on the jaw 37 or sleeve 39 in the direction away from said fixed jaw tends to more firmly bind the seat 21^a about the cone 20^a 80 and prevent the rotation or endwise movement of the screw 15^a, thus locking the jaw firmly in place. The jaw 37 can, nevertheless, be actuated in the usual manner by 85 direct rotation of the screw 15^a.

However, to shift the movable jaw 37 towards the fixed jaw 36, pressure is exerted on the jaw 37 or sleeve 39 in a direction towards the jaw 36, which will tend to 90 separate the cone 20^a and seat 21^a, sufficiently 95 to reduce friction between these parts to a degree such that the worm will be freely rotated by the rack or worm teeth and thus permit the sleeve 39 to slide easily along said outer portion of the head.

In a screw or worm operated wrench of usual form, the operating screw must be rotated in one direction or another to actuate the sliding jaw each time a piece of work 100 is to be secured between the jaws of the wrench, which is a slow procedure. Furthermore, the worm or screw and the rack of the wrench are usually formed with teeth of relatively low pitch, so that the worm is 105 frictionally held from turning under ordinary 110

nary conditions, except when directly turned by the user.

In order to obtain full advantage of the quick acting holding and releasing means described, the worm or operating screw 15^a and the rack teeth 17^a are formed with relatively high pitch or quick lead threads, as shown, so that the screw can be rotated by the rack teeth to permit the movable jaw to be actuated by endwise pressure on the sliding sleeve 12, without separate manipulation of said screw.

I claim as my invention:—

1. In a wrench having a member provided with a fixed jaw, and a movable member having a jaw shiftable toward and from said fixed jaw, the combination of a threaded operating screw journalled on said movable member, teeth on said other member with which said screw engages for actuating said movable jaw, a tapered seat on the latter, a tapered part on said screw engageable with said seat, a flat face on the end of said tapered part, means for yieldingly holding said part frictionally against said seat to prevent said screw from turning and said movable jaw from shifting when pressure is applied thereto in a direction away from said fixed jaw, said movable member having an aperture therein communicating with said tapered seat and into which said end of said tapered part projects, an endwise movable plunger disposed in said aperture and having a recess in one side thereof forming a cam face, a rotatable member disposed in said recess and engaging the side of said tapered screw part and said cam respectively, and said cam being adapted to move said rotatable member along said tapered part and upon said end face thereof to move said part away from said tapered seat upon endwise movement of said plunger in one direction, and a resilient member mounted on said movable jaw and operatively engaging said plunger to move the latter in the opposite direction to return the same, said rotatable member and said screw to normal holding position.
2. In a wrench having a member provided with a fixed jaw, and a movable member having a jaw shiftable toward and from said fixed jaw, the combination of a threaded operating screw journalled on said movable member, teeth on said other member with which said screw engages for actuating said movable jaw, a tapered seat on the latter, a tapered part on said screw engageable with

said seat, a flat face on the end of said tapered part, means for yieldingly holding 55 said part frictionally against said seat to prevent said screw from turning and said movable jaw from shifting when pressure is applied thereto in a direction away from said fixed jaw, said movable member having 60 an aperture therein communicating with said tapered seat and into which said end of said tapered part projects, an endwise movable plunger disposed in said aperture and having a recess in one side thereof forming a 65 cam face, a rotatable member disposed in said recess and engaging the side of said tapered screw part and said cam respectively, and said cam being adapted to move said rotatable member along said tapered part and 70 upon said end face thereof to move said part away from said tapered seat upon endwise movement of said plunger in one direction, and a resilient member mounted on said movable jaw and operatively engaging said 75 plunger to move the latter in the opposite direction to return the same, said rotatable member and said screw to normal holding position.

3. In a wrench having a member provided 80 with a head formed with a fixed jaw, and a movable member having a jaw shiftable toward and from said fixed jaw, the combination of an operating screw journalled on said movable member, teeth on said head with 85 which said screw engages for actuating said movable jaw, said movable jaw having a tapered seat, and said screw having a tapered part engageable with said seat, means for yieldingly holding said tapered part frictionally against said seat to prevent said screw from turning and said movable jaw from moving when pressure is applied thereto in a direction away from said fixed jaw, means operable at will for releasing said 90 tapered screw part from said seat, said head having an open ended slot formed therein, a part on said movable member entering said slot and movable lengthwise thereof for guiding said movable member and holding 95 said screw in operative relation to said fixed jaw, and a part secured to said head for closing the open end of said slot and which is removable to permit said movable member to be detached from said head.

HENRY W. SWITZER.
